UNITED STATES PATENT OFFICE

2,503,363

BLEACHER CONSTRUCTION

Frank C. Torkelson, Salt Lake City, Utah, assignor to Western School Supply Company, Inc., a corporation of Illinois

Application August 8, 1947, Serial No. 767,461

5 Claims. (Cl. 20—1.126)

1

This invention relates to bleacher construction, that is to say, to structures that provide seating facilities for spectators at sports or games.

The principal objects of the invention include those enumerated as follows:

(a) To provide a system of construction based on the employment of a self-contained structural unit, either singly or in multiple, each unit being in the form of a bent having maximum strength and rigidity attained at a minimum expenditure of fabricating labor and material;

(b) A system that is flexible in point of seating capacity;

(c) A system that makes possible the rapid assembling or rapid disassembling of a bleacher structure;

(d) A system in which simplicity and portability are prime considerations.

Other important objects will become evident as the detailed description progresses.

According to the invention, the unit of construction is in the form of a bent composed of triangular panels, these panels being so interrelated that an unusually strong and well balanced seating and walkway structure results. At the same time, economy of fabricating labor and material is an outstanding factor.

The cleancut basic design of the unit bent is readily adaptable to a considerable variation in height, so that by a proper combination of a succession of bents of gradually increasing heights, the upwardly stepped characteristics of conventional bleachers can easily be attained. Moreover, the basic bent design is such that a considerable seating capacity is made possible by uniting the successive unit bents into a composite bent of the required length.

In general, the unit bent pursuant to the invention is characterized by a frame of A-configuration, including two inclined columns meeting at a common vertex, the vertex carrying a seat-supporting upright. The inverted-V panel of the A-configuration is disposed between two V-panels having each substantially one leg in common with a respective leg of the inverted-V panel. Thus, each of the two V-panels has also a respective outboard leg which, at the spread of the V-panel, carries a respective seat-supporting upright similar to the one at the A-vertex, the two outboard uprights however, being at graduated elevations corresponding to the incline line along which the successive rows of seats are arranged. The various seat-supporting uprights are designed to carry respective seat boards in rows similar to any usual bleacher

2

construction. Spaced downwardly from the respective seat boards are walkways as usual, these being supported by structural members that advantageously and largely, constitute parts of the respective unit bents.

The bents are spaced apart one from another along the length of the seats and walkways to suit the allowable spans of the seat boards and walkway boards.

In the accompanying drawing, which illustrates one specific embodiment of the invention,

Fig. 1 represents a side elevation of a bleacher construction, showing the manner in which a series of unit bents of different heights is combined to form a composite bent on which the successive rows of seats and the associated walkways are supported in substantially uniformly ascending order;

Fig. 2, a fragmentary plan showing portions of seats and walkways; and

Fig. 3, a fragmentary rear elevation showing several consecutive ranges of composite bents in transversely braced relation one to another.

Referring to the drawing, the numeral 10 denotes substantially a finished bleacher structure built on a suitable surface such as turf or a suitably leveled piece of ground 11. The assemblage 10 includes mainly a series of transversely spaced composite bents 12, 12a, 12b, and so on, indefinitely, these being braced for example, in pairs, as shown at 13 and 13a, Fig. 3. The assemblage further includes seats 14, 14a and 14b in spaced groups, as well as walkways 15, 15a and 15b in spaced groups that correspond to the respective groups of seats, all as shown in Fig. 1.

Commencing at the left of Fig. 1, a series of unit bents 16, 17, 18, 19 and 20 is arranged so the respective seats and walkways supported by these bents are in gradually descending order. Of the bents 16, 17 and 18, the A-frames 21, 22 and 23 comprise the basic components. The respective A-frames consist principally of inclined front legs or columns 24, 25 and 26, together with inclined rear legs or columns 27, 28 and 29, the respective pairs of legs being joined at a common vertex and having each an intermediate tie 31.

Extending as columns outwardly and inclining upwardly from the front legs 24, 25 and 26, are front branches or outboard legs 31, 32 and 33, respectively, and extending in a similar manner from rear legs 27, 28 and 29, are the respective rear branches or outboard legs 34, 35 and 36. Each of the various front and rear branches is

connected to its respective A-frame by means of a tie 37.

Springing, that is to say, extending upwardly from the vertices of the A-frames 21, 22 and 23, are uprights 38, from the upper portions of front outboard legs 31, 32 and 33 are uprights 39, and from the upper portions of rear outboard legs 34, 35 and 36 are uprights 40. Secured to the uprights 38, 39 and 40 are the various cross pieces 41, which carry the respective groups of seats 14, 14a and 14b.

The basal spread of all the A-frames is preferably equal one to another and the lower extremities of the A-frame legs are secured to the base members 42, the bearing areas of the latter on the supporting surface of soil, turf, or other constituent being proportioned in accordance with good engineering practice.

In the present instance, the A-frames with the front and rear branches and the connections just outlined are assumed to be fabricated from structural steel, preferably angles, and all joints between the component members are assumed to be welded. Thus, each bent is a self-contained, integrated unit wherein the fabricating expense and the amount of material required are both reduced to a practicable minimum.

Novel characteristics that contribute to economical construction combined with maximum strength, consist largely of arrangement of the V-panels embodied in the unit bents. For illustration, each A-frame has an inverted-V panel 43 within the configuration of the A, and two flanking V-panels, 44 and 45, contiguous thereto. Thus, each V-panel has one independent outboard leg and one leg in common with the inverted-V panel.

The unit bent 19 conforms in general to the characteristics of the A-frame unit bents, it being considered that the A-legs are shortened and the outboard legs arranged substantially vertically. In the bent 19 the inverted-V panel appears at 46 and the flanking V-panels at 47. The unit bent 20 is not particularly unique, but is provided as a matter of convenience to support the first few rows of seats and walkways.

The individual unit bents are adapted for shop fabrication complete. All that is necessary in field erection is to put the upper ties 48 and the lower ties 49 in place, applying bolts 50 where portability is desired, or else riveting or welding the connections for relatively permanent installations. In any event, the unit bents are serviceably connected one to another to form the composite bents. Obviously as many or as few of the unit bents are used as may be determined by the desired seating capacity of the finished bleacher structure.

While a specific embodiment of the invention is herein shown and described, the scope of the invention is limited only by the following claims.

What is claimed is:

1. A bleacher bent, including in combination, two inclined columns constituting an inverted-V panel; an auxiliary column intersecting one of the inclined columns intermediate the length of the said one inclined column, a second auxiliary

column intersecting the other of the inclined columns intermediate the length of the said other inclined column, an upright rising at the vertex of said inclined columns; uprights rising from respective auxiliary columns, seat supporting means mounted on each of said uprights; and walkway supporting means disposed between said seat supporting uprights.

2. A bleacher bent according to claim 1, wherein in said walkway supporting means comprises structural members tying said auxiliary columns to said inclined columns.

3. A bleacher bent according to claim 1, wherein the lower terminal portions of said inclined columns of said inverted-V panel are integrally tied together by means of a structural base member.

4. In a bleacher construction, a system of bents of graduated heights tied together into a composite bent, the respective bents each comprising two inclined columns joined at a common vertex and joined intermediate their lengths by a cross tie forming an A frame and inverted-V panel; an auxiliary column joined to one of said inclined columns adjacent the cross tie and rising divergently outwardly therefrom to form a V panel flanking the inverted-V panel; a second auxiliary column joined to the other of said inclined columns adjacent the cross tie and rising divergently outwardly therefrom to form a second V panel flanking the inverted-V panel opposite the first V panel; cross ties joining the respective auxiliary columns with the said inclined columns, said cross ties forming walkway supports; seat-supporting means supported by the upper ends of said auxiliary columns and said joined inclined columns; and structural members joining said respective bents together.

5. A structural bent for bleacher construction comprising two inclined columns joined at a common vertex and joined intermediate their lengths by a cross tie forming an A frame and inverted-V panel; an auxiliary column joined to one of said inclined columns adjacent the cross tie and rising divergently outwardly therefrom to form a V panel flanking the inverted-V panel; a second auxiliary column joined to the other of said inclined columns adjacent the cross tie and rising divergently outwardly therefrom to form a second V panel flanking the inverted-V panel opposite the first V panel; cross ties joining the respective auxiliary columns with the said inclined columns, said cross ties forming walkway supports; and seat-supporting means supported by the upper ends of said auxiliary columns and said joined inclined columns.
